UNITED STATES PATENT OFFICE.

ELMER K. COLE AND CHARLES E. HANDEL, OF WINTERSSET, IOWA.

EARTH ANCHOR DEVICE.

Application filed January 13, 1926. Serial No. 31,991.

The object of our invention is to provide an earth anchor device of simple, durable and inexpensive construction, especially designed for use in supporting guy wires for poles and the like.

More specifically it is our object to provide an anchor device which may be inserted in the earth in a hole of relatively small diameter, and in which the anchor blades may then be positively and uniformly forced outwardly into the earth surrounding the opening, to thereby grip a relatively large area of earth surrounding the opening; and

Further in this connection it is our object to provide a means for expanding the anchor blades whereby they may be expanded in a convenient and facile manner.

A further object is to provide a device of this character in which the anchor head and blades may be formed of cast metal and readily and quickly assembled in position for operation without any machine work, whereby the cost of construction is minimized.

A further object is to provide a device of this character in which when the blade expanding head has been moved to its limit in a direction for expanding the blades, it will then engage a locking shoulder on the blades and form a locking device to prevent further outward movement of the blades, and to lock the blades in their fully extended position, to thereby form a locking support for the blades on both sides of the blade pivots to relieve the pivots of strain and to materially strengthen the structure.

Our invention consists in the construction, arrangement and combinations of the various parts of the device, whereby the objects contemplated are attained, as hereinafter more fully set forth, pointed out in our claims, and illustrated in the accompanying drawings, in which:

Figure 1 shows a side elevation of our improved anchor device shown in its folded position within an opening formed in the earth to receive it. The dotted lines in said figure show the blades in their expanded position ready for use.

Figure 2 shows an enlarged, detail, vertical, sectional view of the head and spreading and locking plate with two blades shown in an extended and locked position; and

Figure 3 shows an inverted plan view of the expanding and locking plate.

Referring to the accompanying drawings,

we have used the reference numeral 10 to indicate the body portion of our device. This is preferably cast complete of a single piece of metal and has a screw threaded opening extended through its central portion. On each of its four sides recesses 11 are formed, and across each recess there is a pivot bar 12 formed integral with a head 10. Each pivot bar is substantially oval in cross section, its major axis extending upwardly and outwardly from the bottom of the body portion 10, as clearly shown in Figure 2. Inserted in the screw threaded opening of the body 10 is the anchoring rod 13, its lower end being screw threaded. It is provided with a nut 14 at the upper part of the screw threaded portion.

Slidably mounted upon the screw threaded portion of the rod 13 below the nut 14 is the combined expanding and locking head comprising a flat body portion 15 provided with radial reinforcing ribs 16 on its upper surface, and with marginal downwardly extended locking ribs 17 on its under surface. This blade is preferably octagonal in shape, thus forming eight of the locking ribs 17 of equal size.

Four anchoring blades are provided. Each anchor blade comprises a body portion 18 curved in the manner shown in Figure 2, and provided on its under or outer surface with a longitudinal reinforcing rib 19. Each blade is pointed at its outer central portion, as clearly shown at 20 in Figure 1.

Formed on the lower inner end of each blade is a rounded curved guide pin 21, and spaced above the guide pin 21 is a shoulder at 22. Extending inwardly and above the shoulder 22 there is a locking rib 23 extended upwardly, as clearly shown in Figure 2. Between the pin 21 and the shoulder 22 there is a space provided in which the pivot bar 12 may be received. In this connection, the relative shapes and sizes of the pivot bar 12, the recess 11, the locking pin 21 and the shoulder 22 are such that when the body of the blade 18 is placed in position extended upwardly and inwardly to a position where they would touch the rod 13, the blades will be removed from the bars 12, but when the upper ends of the blades are turned outwardly a short distance from the rod 13, they cannot be thus removed. When the expanding and locking plate 15 is in position as shown in Figure

1, then the blades cannot be thus removed, and this is the position in which the device is prepared for shipment, handling and use.

In order that the anchor blades may fold 5 in a relatively compact manner, we preferably form two of the blades on opposite sides with concaved side edges, clearly shown in Figure 1, and the two on opposite sides with convexed side edges, as shown by the 10 shaded lines in Figure 1, so that when assembled as shown, they will occupy a minimum of space.

In practice, it is obvious that the device 15 may be constructed almost entirely of cast metal and without machine work. The only machine work required is the threads on the rod 13 and the screw threaded opening in the body 10.

In assembling the device the blades are 20 placed in position substantially parallel with the rod 15 and the extensions 21 are inserted in the recesses 11. Then the rod 13 is screwed into the body 10 to the position shown in Figure 1, and when in this position 25 the device is ready for shipment and use.

In the use of our device the operator first forms a round opening by boring or otherwise, in the ground. The diameter of the 20 opening need not be any greater than the diameter of the folded anchoring device. Then the anchoring device is placed in position near the bottom of the opening and the points of the anchor blades are made to engage the earth at the sides of the opening. Then the operator takes a crowbar or the like and extends it through the eye in the upper end of the rod 13 and imparts a rotary movement to the rod. This gradually forces the body 10 upwardly toward the expanding and locking plate 15, which does not move. When this is being done, the points of the anchoring blades will be moved outwardly and upwardly into the earth to the position shown by dotted lines in Figure 1, and when this movement has been completed, the locking ribs 17 will then engage the corresponding locking ribs 23 on the anchoring blades, and thus limit 45 the movement of the body portion 10 toward the expanding and locking plate, and at the same time lock the anchor blades firmly and immovably in the position shown in Figure 2. When tension is applied to the rod 13 and the anchoring blades are in the ground, as shown by dotted lines in Figure 1, then this tension as applied to the blades will 50 tend to swing the blades further outwardly.

However, the locking ribs 17 and 23 serve to prevent such movement, and thereby relieve the bars 12 from any strains because the lower ends of the anchor blades engage the body 10.

By having the expanding and locking plate made octagonal in shape with ribs 17 60 at all sides, then it does not matter in what position the expanding and locking plate may be, because some of the ribs 14 will always engage the corresponding ribs 23 of the anchoring blades.

We claim as our invention:

1. An anchoring device of the class described, comprising in combination a body portion, an anchor rod having a screw connection with said body portion, a series of 75 blades pivoted to the body portion and capable in one position of standing nearly parallel with the anchor rod and in another position of inclining outwardly, a spreader plate mounted on said anchor rod and designed to engage the inner surface of the blades and force them outwardly when the anchor rod is rotated to move the body portion toward the spreader plate, locking lugs 80 on the inner surface of the blades, and coacting locking lugs on the spreader plate designed to engage the locking lugs on the blade to thereby limit their outward movement.

2. In a device of the class described, the combination of a body formed with a central screw threaded opening and with recesses at its sides and a pivot bar extended across each recess, a series of anchor blades formed with projections to enter said recesses 90 below said pivot bars and also formed with locking lugs above said pivot bars and capable of a swinging movement from a position extended substantially straight upwardly to a position extended outwardly 100 and upwardly, a screw threaded rod extended through said screw threaded opening in the body, and an expanding and locking plate rotatively mounted on the screw threaded rod and having its side edges designed to engage the inner upper face of the anchor blades to cause them to move outwardly when the body portion is moved upwardly on the screw threaded rod, said plate being formed with downwardly extended locking lugs at its edges designed to engage the locking lugs on the blades when the blades have reached their outward limit of movement.
